BAKER'S PEEL

Louis Portner, Margate City, N. J.

Application March 31, 1948, Serial No. 18,120

4 Claims. (Cl. 107—67)

1

My invention relates to a baker's peel and has for an object to provide a peel which will materially lessen the effort in making what are known as "Kaiser" rolls.

As is well known to those skilled in the art, a Kaiser roll is a roll wherein the upper surface is scored or impressed either by hand or by an automatic machine, so that after the roll is baked, it may easily be broken in the hand and the divisions follow the certain lines that have been previously scored or formed in the roll.

As is also well known, in the making of these bakers' rolls, after they have been scored or imprinted, they are laid on a table or on a baker's peel, with the top-side down and left there to rise for about an hour. The purpose of letting them rise in their face-down position is so that the score or indentation previously formed in them will remain during the rising period; then when these rolls are to be placed in the baking ovens, it is necessary for the baker or a helper to turn these rolls over, that were bottom-up, and place them on a peel so that the peel can be placed in the oven door, then tilted, and the rolls placed in the oven bottom-side down.

One of the objects of the present invention, therefore, is to provide a baker's peel so that a number of rolls, say, twenty-five, can be placed on a convenient-sized peel; and after the dough has risen, one lever may be revolved 90° to turn over all the rolls on the peel at one time, so that they will then be bottom-side down and will easily slide into the oven.

In other words, instead of turning by hand each of the twenty-five Kaiser rolls singly, by manipulation of a lever to operate vanes that are mounted on the peel board, all twenty-five rolls may be turned with but a motion of the thumb and fingers.

Still another object of the invention is to provide a baker's peel which consists of a conventional blade or body portion and handle, while superimposed on the blade is a plurality of adjacent vanes or leaves which normally lie flat on the body portion, these vanes being inter-connected and capable of being elevated 90° by the manipulation of one small lever, so that the Kaiser rolls (dough) that have been positioned on these vanes may be turned from top-side down to top-side up, by simply raising these vanes 90° through the movement of a small lever connected to one of the vanes.

Still another object of the invention is to provide a conventional-size peel with approximately five vanes or leaves that are co-extensive with

2

the length of the peel board, and wide enough to leave channels between the vanes when they are elevated, so that all of the rolls on the board may easily be reversed in position, then the board tilted so that the now properly positioned rolls (dough) may easily slide into the receptive ovens.

With these and other objects in view, the invention consists in certain new and novel arrangements and combination of parts as will 10 hereinafter be more fully described and pointed out in the claims.

Referring now to the drawings, showing a preferred embodiment,

Fig. 1 is a perspective of my improved baker's 15 peel, the dotted lines showing how the rolls (dough) would be placed thereon,

Fig. 2 is a front end view, parts being broken away, and parts being in dotted lines to show the actuated position of the vanes,

Fig. 3 is a sectional view taken on line 3—3 of Fig. 2, looking in the direction of the arrows, and

Fig. 4 is an enlarged, fragmentary perspective, showing the vanes in their elevated position.

At the outset it will be understood that I have 25 shown a baker's peel with five vanes thereon, and which peel will accommodate about twenty-five Kaiser rolls; but the peel might be made with either less or more vanes, if so desired.

Referring now more particularly to the several 30 views, and for the moment, to Fig. 1, there is shown the blade or body portion 1, with the integral handle 2, this body portion 1 and handle 2 being a conventional one. However, instead of just using this plain blade and handle, I pivotally 35 mount a plurality of plates or vanes 3 thereon, which normally lie flat, as shown in Fig. 1.

Glancing at Fig. 3, for the moment, I have 40 shown the method of hinging these plates or vanes 3 to the body portion 1, and it will be understood that a description of one is a description of all.

Near the distal end of the vane 3 may be seen the hinge 4 and at the proximal end, the hinge 5, the hinges 4 and 5, of course, being secured to 45 the blade 1 and to the vane 3.

Also secured as at 7 to the proximal end of the central vane 3 is the small lever 6, this lever 6 bent outwardly at its outer end to form the small handle 8, and the lever 6 being held in position 50 by the eyelet or staple 9.

These vanes 3 are inter-connected at their proximal end by the cross-bar 10, pivots 11 securing the bar 10 to the respective vanes or leaves 3.

At the right hand side of the board 1 there is

a reduced size vane 12 which simply acts as a rail to prevent the rolls (dough) from falling off the one side of the peel after they have been turned, as will be described shortly.

In Fig. 2, I have shown what is known as a Kaiser roll 13, which has been scored as at 14 either by hand or by an automatic machine; and it will be understood that each disk of dough, which has been scored (and which disks will eventually form the rolls) will be placed in a line adjacent to each other from the lower end to the upper end of the peel on the respective vanes 3 with their top-sides down as shown in Fig. 2.

Here the dough disks are allowed to rise for about an hour, and by placing them with their face-down, which is the usual practice, the dough retains the score or division marks there-in as the dough rises.

After the dough disks have been allowed to rise for about one hour, and it is desired to place them in the oven, the operator will simply grasp the handle 8 and turn it from the position shown in Fig. 1 to the position shown in Fig. 4, and as will be seen in Fig. 2, the scored dough in its disk shape, will all be turned bottom-side up so that the disks (now risen dough) will assume the position as shown in dotted lines in Fig. 2.

It will be understood that the pre-shaped and risen dough is moist or sticky enough so that the rolls (dough) do not slide from the vane over into the receptive channel, but will be completely turned over as heretofore described.

It will also be seen that when the vanes 3 are in their uppermost or vertical position, there are resultant channels 15 between the respective vanes 3, and, of course, the outermost guide 12 so that the rolls may slide off the peel.

Then while the vanes 3 are in their vertical position as shown in Figs. 2, 3 and 4, the peel will be placed in the oven door and tilted until the rolls (or dough that forms the rolls) slide down in their respective channels, bottom-side down, into the oven. Then, when the peel is withdrawn, the handle 8 is again swung downwardly to the position shown in Fig. 1; and then again the operation is repeated.

From the foregoing, it will be seen that I have provided a baker's peel wherein using, say, a conventional-size peel, the twenty-five pieces of dough that will form the rolls may be reversed with but one operation; rather than turning each of the twenty-five pieces of dough by hand; and when it is appreciated that where thousands of rolls are to be baked in one evening, by providing a number of these peel boards, the time saved in turning twenty-five at once will readily be appreciated.

As heretofore mentioned, the peels may be of different width and may have more or less vanes than that illustrated, although I have found one with five vanes a convenient size for the baker to handle.

Many slight changes might be made without departing from the spirit and scope of the invention.

Having thus described my invention, what I claim is new and desire to secure by Letters Patent is:

1. A baker's peel for holding and turning Kaiser rolls, comprising a blade and handle extending therefrom, a plurality of superimposed vanes pivotally mounted on the blade, means inter-connecting the said vanes, and means connected with one of said vanes to elevate all of said vanes when operated, whereby the pre-shaped dough placed on said vanes will simultaneously be turned from bottoms-up to bottoms-down position.

2. A baker's peel, comprising a blade and handle extending therefrom, a plurality of superimposed pivotal vanes, substantially co-extensive in height with the said blade, and lying normally in a horizontal position, a crossbar pivotally connected to said vanes, and a handle connected with one of said vanes, which, when operated, will simultaneously raise all the vanes from the horizontal to the vertical position.

3. A baker's peel, comprising a blade and handle extending therefrom, a plurality of hinged vanes mounted thereon, whose combined width is substantially co-extensive with the width of the blade, said vanes lying normally in a horizontal position, a cross-bar, pivotally connected to said vanes, and means connected with one of said vanes for simultaneously raising all of the vanes from the horizontal to the vertical position.

4. A baker's peel, for use in turning Kaiser rolls, comprising a blade and handle extending therefrom, a plurality of hinged vanes, a side rail, the combined width of the side rail and the vanes being substantially that of the blade, said vanes and guard rail normally lying in a horizontal position, a cross-bar pivotally connected to all of said vanes and said guard rail, a handle connected with one vane, which, when operated, will simultaneously raise all of the vanes and the guard rail from the horizontal to the vertical position, the width of the vanes being such that when elevated will form resultant channels between the vanes, adapted to receive the Kaiser rolls when turned by the raising of said vanes.
